UNITED STATES PATENT OFFICE.

CHARLES S. RAIA, OF GARFIELD, NEW JERSEY.

ICE-CREAM CUTTER.

1,343,932.

Specification of Letters Patent. Patented June 22, 1920.

Application filed February 11, 1920. Serial No. 357,804.

To all whom it may concern:

Be it known that I, CHARLES S. RAIA, a citizen of the United States, residing at Garfield, in the county of Bergen and State of New Jersey, have invented certain new and useful Improvements in Ice-Cream Cutters, of which the following is a specification.

This invention has relation to a cutting machine, and has for an object to provide a machine designed particularly to sever a block of ice cream into a large number of portions, in an effective and expeditious manner.

Another object of the invention is to provide a machine of the character above set forth including a plurality of vertically movable knives designed to cut the ice cream, and means for heating said knives whereby they may accomplish their work more effectively.

In addition to the foregoing this invention comprehends improvements in the details of construction and arrangement of parts, to be hereinafter described and particularly set forth in the appended claims.

In the accompanying drawings in which similar and corresponding parts are designated by the same characters of reference throughout the several views in which they appear:

Figure 1 is a view in front elevation of a machine constructed in accordance with my invention.

Fig. 2 is a vertical section thereof.

Fig. 3 is a transverse horizontal section. With reference to the drawings, 10 indicates a table upon which a rectangular open-work frame 11 is mounted. Depending from within the frame 11 is a bracket 12 supporting a frame 13 from which a plurality of heaters 14 depends, each heater being rectangular and hollow and preferably having their lower edges beveled inwardly as at 15. The heaters 14 may be of metal, and I provide a heating means consisting of a pipe 16 extending centrally of the frame 13 and provided with a plurality of lateral branches 17 which are perforated and extend into the boxes 14. The pipe 16 is designed to be attached to a source of gas supply which may be ignited at the openings of the extension 17, the flame acting to heat the sides of the heater.

The table 10 is provided with a pair of openings through which extend the vertical members 18 of a frame work, said members

carrying at their upper end a rectangular casing 19 which is formed with a ledge 20 at its lower end. Located within the frame are a plurality of longitudinally extending blades 21, and transversely extending blades 22 arranged at right angles. Each blade is slotted as at 23 so that the blades of one set may be received within the blades of the other and vice versa. The end of each blade is also reduced in width as at 24 so as to rest upon the ledge 20, and strips 25 are then located within the upper end of the frame to seat within the recess or reduced portions of the blade to secure the latter in place. Opposite sides of the frame 19 are formed with dove tailed slots 26 in which dove tails 27 formed upon plates 28 are received, said plates being secured to the inner faces of the frame members 18. The frame 18 is provided with a cross piece 29 the ends of which are extended beyond the frame and have springs 30 connected thereto, the other ends of said springs being connected to the table so as to normally retain the frame in an upward position. Guide rod 31 extending from the table and entering openings in the ends of the strip 29 are also provided to guide the member 18. A foot lever 32 is pivoted at the lower end of the frame and is connected to the frame 18 so as to move the latter downward when the lever is stepped upon.

In use a block of ice cream or the like is placed upon the upper side of the table 10 beneath the frame 19 and the latter is moved downward in the manner described above whereupon the block of ice cream is divided into a plurality of portions. It will be apparent that while the knife casing is in an elevated position it becomes heated by radiation from the heaters 14 and the heated knives thus sever the ice cream more readily and insure the separation of the portions of ice cream from the knives so that the knife blades can be readily withdrawn again. It will be apparent that I may heat the heaters 14 by electricity instead of gas. Other variations may be readily made in the structure herein described.

While I have illustrated and described my invention with some degree of particularity, I realize that in practice various alterations therein may be made. I therefore reserve the right and privilege of changing the form of the details of construction or otherwise altering the arrangement of the cor-

related parts without departing from the spirit of the invention or the scope of the appended claims.

Having thus described my invention, what I claim as new and desire to secure by United States Letters Patent is:

- 5 1. A cutting machine comprising a table, a rectangular frame arranged thereover for vertical movement, a plurality of blades carried within the frame arranged at rightangles and defining compartments therebetween, a heater comprising a plurality of rectangular members designed to enter said compartments, springs for urging the frame upward, and a positive means for moving the same downward.

2. A cutting machine comprising a table, a frame mounted thereover for vertical movement, a plurality of blades arranged within the frame at relative rightangles defining compartments therebetween, a bracket mounted above the frame, a plurality of hollow rectangular heaters mounted in spaced relation depending from the bracket to enter the compartments when the frame is elevated, means for heating said rectangular heaters, springs for urging the frame upward, and a positive means for moving the frame downward.

In testimony whereof I affix my signature. 30

CHARLES S. RAIA. [L. S.]
